UNITED STATES PATENT OFFICE.

ADOLF FRANK RUSS, OF PITTSBURGH, PENNSYLVANIA.

AEROPLANE-WING.

1,213,909.

Specification of Letters Patent. Patented Jan. 30, 1917.

Application filed March 31, 1916. Serial No. 88,126.

To all whom it may concern:

Be it known that I, ADOLF FRANK Russ, residing at Pittsburgh, in the county of Allegheny and State of Pennsylvania, a citizen of the United States, have invented or discovered certain new and useful Improvements in Aeroplane-Wings, of which improvement the following is a specification.

The object of my invention is to provide a supporting wing for aeroplanes which will have a flexible lower surface capable of automatically conforming to the curvature which will most efficiently satisfy the varying requirements of such wings.

15 In the accompanying sheet of drawings I have illustrated the preferred embodiment of my invention.

Figure 1 is a plan view of the aeroplane wing; and Figs. 2 and 3 are sectional views taken, respectively, on the lines II—II and III—III, Fig. 1.

20 In the practice of my invention I provide a frame to which there are secured upper and lower membranes, the lower membrane 25 although stretched tautly on the edge members of the frame, being flexible and unsupported by intermediate frame members. As far as concerns the broad features of my 30 invention, the wing may be of any desired shape and the upper membrane may be either fixed or flexible.

The wing shown in the drawings is triangular in shape, the frame consisting of stays 1, 2 and 3 in the forward, rearward 35 and inner edges of the wing, braces 4 extending from the stay 3 to the outer end or corner of the wing, and braces 5 extending between the edge stays 1 and 2. The front and rear edge stays 1 and 2 are substantially 40 flat members, while the inner stay 3 is of the shape indicated by the cross-section of the wing as seen in Fig. 2, that is to say it has a convex upper side and, except for small end portions, the lower side is slightly concave.

45 As will be seen from Figs. 2 and 3, the braces 5 are arched to conform to the general shape of the top of the stay 3, and the braces 4 are secured to the braces 5. The upper membrane 6 is secured to and held in fixed position upon the upper side of the frame, while the lower membrane is stretched tautly between and secured to the lower edges of the stays 1, 2 and 3. The lower membrane 7

may be made of fabric or any suitable flexible material which will yield slightly to the 55 variable air pressure upon it.

The wing which I have shown and described may be used upon any desired form of aeroplane, but it is particularly suitable for aeroplanes such as shown in my copending application, Serial No. 88,127, filed of even date herewith. It is well known that when aeroplanes are gliding, or traveling in a semi-gliding manner, the usual concavity on the lower sustaining face of the wing causes 65 an undue amount of head resistance. This undesirable feature is largely overcome by the wing which I have provided, for the lower membrane is but slightly concave when the machine is traveling as indicated, and 70 hence offers no unnecessary resistance. On the other hand, when the wing is inclined upwardly to cause the aeroplane to rise, the increased pressure of the air against the flexible lower membrane causes it to arch in 75 the manner indicated by the dotted lines 9 in Figs. 2 and 3, so that the sustaining surface will then have the proper configuration to afford the maximum lifting effect. Thus it is seen that, in the wing which I provide 80 the variations in air pressure upon it causes the sustaining surface automatically to conform to the curvature best suited to most effectively satisfy the varying requirements.

According to the provisions of the patent 85 statutes, I have described the principle and operation of my improved aeroplane wing, together with the construction which I now consider to represent the best embodiment thereof. However, I desire to have it understood that the wing which I have shown 90 is only illustrative, and that my invention may be practised in other forms of wings than that shown.

I claim as my invention:

1. An aeroplane wing comprising an arched frame having marginal stays and intermediate cross-braces, an upper membrane secured to and held in fixed position upon the upper side of said frame, and a flexible 100 lower membrane secured to the marginal stays of said frame and unsupported by the other frame members.

2. An aeroplane wing of triangular shape comprising an arched frame having marginal stays at the three edges of the wing 105

and intermediate cross-braces, an upper membrane secured to and held in fixed position upon the upper side of said frame, and a flexible lower membrane stretched tautly 5 between and secured to the marginal stays of said frame and unsupported by the other frame members, said membranes being separated a substantial space at the inner wing edge and gradually tapering to meeting lines at the front and rear wing edges. 10

ADOLF FRANK RUSS.
